(57) **CLAIM**

The ornamental design for an antenna layout for contactless data card, as shown and described.

DESCRIPTION

FIG. 1 is a perspective view of an antenna layout for contactless data card according to my new design;

FIG. 2 is a front elevation view thereof;

FIG. 3 is left side view elevation view thereof;

FIG. 4 is a right side elevation view thereof;

FIG. 5 is a rear elevation view thereof;

FIG. 6 is a top view thereof; and,

FIG. 7 is a bottom thereof.

The broken lines in FIGS. 1, 2 and 5 illustrate portions of the data card which form no part of the claimed design.
